FREDERICK W. GEAR, OF NEW YORK, N. Y.

SPARK-PLUG.

1,264,055.

Specification of Letters Patent. Patented Apr. 23, 1918.

Application filed March 28, 1916. Serial No. 87,181.

To all whom it may concern:

Be it known that I, FREDERICK W. GEAR, a subject of the King of Great Britain, and a resident of the borough of Manhattan, in the city, county, and State of New York, have invented certain new and useful Improvements in Spark-Plugs, of which the following is a specification.

One object of this invention is to provide a spark plug with an auxiliary tell-tale spark gap which raises the voltage at the main gap and thereby increases the efficacy of the ignition spark, and also indicates to the eye whether the plug is performing or not. It has been heretofore proposed to provide spark plugs with such auxiliary gaps, but in order to render them visible and still to avoid risk of igniting explosive vapors about the engine, they have been housed within impervious transparent walls. In such constructions, the auxiliary gap is surrounded by a body of trapped air which becomes heated and altered by the continued passing of the auxiliary spark therein, with the result that the resistance is varied and the action of the plug rendered unreliable. Furthermore, the materials used, glass, mica, etc., are breakable and give rise to danger of serious explosions. I overcome these difficulties and make the tell-tale spark gap safe and practicable by disposing it in an open chamber which is guarded by a gauze or screen; the screen permitting the air at the gap to be renewed and retaining the advantage of visibility while preventing all outward propagation of flame. In this way the performance of the plug is made uniform and safety is insured. The invention accordingly comprises a spark plug having a gauze-guarded tell-tale spark gap, and also certain preferred constructional features in relation thereto.

In the accompanying drawings illustrating the preferred embodiment of the plug: Figure 1 is an elevation; Fig. 2 is a longitudinal section; Fig. 3 is a view looking at the inner end of the plug; and Fig. 4 is a cross-section on the line 4—4 of Fig. 2.

The structural part of the shell, as preferably embodied, includes an inner shell 1 and an outer shell 2. The inner shell is screwed into the cylinder wall in the usual manner, being thereby included in the sparking circuit, which is grounded on the

engine as well understood. The outer shell, so termed because it is located outside the engine cylinder, is screwed into the inner shell, as shown at 4. The two shells inclose 60 a cavity wherein is held a core 5, of suitable insulating material, having an enlargement 6, which is held between opposed shoulders 7 and 8 on the two shells, respectively. Compressible washers 9 and 9^a are interposed between the shoulders and the enlargement to prevent injury to the core when the outer shell is screwed home, and to secure tight joints.

Through this core passes a conductor rod 70 section 10, the inner end of which constitutes one of the terminals of the main or ignition spark gap. The other terminal, in the particular instance illustrated, is formed by the edge of a restricted central opening 75 11 in an end wall 12 of the inner shell, which end wall separates a chamber 13 from the combustion space of the engine cylinder.

The outer portion of the said rod section bears a nut 14, which clamps the rod in place 80 in the core, and is extended beyond this nut into a chamber 15 in the outer part of the plug, that is to say the portion of the plug which is external to the engine cylinder. Preferably this chamber is formed in a 85 second insulating core 16, which is inserted into the outer shell 2, the said core and shell being provided with lateral openings 17 which register when the device is assembled, as seen in Figs. 2 and 4. These openings 90 are for sight and ventilation, and are guarded by a tubular wire gauze 18, which is preferably slipped onto a reduced portion 19 of the core, so as to be firmly supported and held laterally between the core and shell, 95 which also prevent endwise displacement of the gauze by means of shoulders 20 and 21. The said chamber incloses the auxiliary spark gap, which is formed by the spaced ends of the rod section 10 and a second rod 100 section 22 passing through the outer end of the core 16. Adjustment of this spark gap is preferably provided for by making the rod 22 in the form of a screw having a suitable electrode tip 23, the threads of the 105 screw engaging internal threads formed in the axial opening through the outer part of the said core 16. A cap 24, of insulating material takes over the end of the outer shell 2 and has a plain central aperture 110 through which the screw passes loosely. A nut 25 on the outer portion of the screw is

used to lock the adjustment of the auxiliary spark gap at any desired point, and also coöperates with the screw to hold the several elements of the outer part of the plug in assembled relation. In this connection it will be observed that the core 16 is formed with an outward facing shoulder 26 which abuts against the internal shoulder 21, in the shell 2, so that when the said nut is 10 screwed forcibly up against the cap 24, not only is the latter held in place but the said core and shell are also drawn together, and in this way, further, the gauze is locked in place. Manifestly, however, these details of 15 construction, while desirable, may be considerably varied. Another nut 27 on the screw serves to bind the terminal of the external conductor to the central conductor of the plug.

20 The important functions of the open chamber 16 and the gauze in connection with the auxiliary spark gap have already been explained, and the operation thereof will be readily understood.

25 The chamber 13 heretofore mentioned keeps the main terminals free of carbon deposits, because of the dislodging effect of the explosion of gas pocketed therein. Additional small openings 28 are shown in the 30 wall of this chamber at opposite sides of the central opening, in order to insure the admission thereto of a portion of the several explosive charges compressed in the engine cylinder preparatory to firing.

35 While I have illustrated and described one embodiment of my invention, it will be understood that numerous other and different embodiments may be constructed containing the same essentials, and that I do not 40 limit myself to the precise details herein set forth.

What I claim as new is:

1. A spark plug, comprising inner and

outer shells screwed together, an inner core of insulating material within the inner shell, 45 an electrode rod passing through said inner core, an outer core of insulating material within the outer shell, said core having a chambered reduced portion leaving an annular space between the same and the encircling inner surface of the outer shell, said reduced portion and the outer shell having lateral openings for sight and ventilation, a tubular gauze slipped onto said reduced portion and confined within said annular space, and a second electrode rod passing 50 through the outer part of the outer core and terminating in the chamber thereof at a distance from the outer end of the other rod.

2. A spark plug, comprising inner and outer shells screwed together, an inner core of insulating material within the inner shell, an electrode rod passing through said inner core, an outer core of insulating material 55 within the outer shell, said core having a chambered reduced portion leaving an annular space between the same and the encircling inner surface of the outer shell, said reduced portion and the outer shell having lateral openings for sight and ventilation, a tubular gauze slipped onto said reduced portion and confined within said annular space, and a second electrode rod passing through 60 the outer part of the outer core and terminating in the chamber thereof at a distance from the outer end of the other rod, the outer shell and outer core having abutting shoulders, a cap of insulating material covering the outer end of the outer shell, and a nut 65 on the outer rod outside of the cap and co-operative with said rod to draw the outer core against the shoulder of the outer shell and to clamp said shell and core and the cap together.

FREDERICK W. GEAR.
